Attorney

UNITED STATES PATENT OFFICE.

NORMAN W. CUMMINS, OF BRIDGEPORT, CONNECTICUT, ASSIGNOR TO THE BASSICK CO.,
OF BRIDGEPORT, CONNECTICUT, A CORPORATION OF CONNECTICUT.

LUBRICATOR.

1,269,685.

Specification of Letters Patent. Patented June 18, 1918.

Application filed February 5, 1918. Serial No. 215,474.

To all whom it may concern:

Be it known that I, NORMAN W. CUMMINS, a citizen of the United States, residing at the city of Bridgeport, county of Fairfield, 5 and State of Connecticut, have invented certain new and useful Improvements in Lubricators; and I do declare the following to be a full, clear, and exact description of the invention, such as will enable others skilled in the art to which it appertains to 10 make and use the same.

This invention relates to certain new and useful improvements in a lubricator for hollow bolts and it has for its primary object 15 to provide a reinforcing plug for sheet metal closure caps which will present a solid head for driving purposes and thus prevent the closure cap from becoming crushed.

Further, the invention resides in the features of construction hereinafter specifically pointed out and succinctly claimed, reference being had to the accompanying drawing wherein—

Figure 1 is a longitudinal section through 25 a bolt and the lubricator applied thereto;

Fig. 2 is a transverse section thereof on line 2—2 of Fig. 1;

Fig. 3 is a longitudinal section through the lubricator *per se*; and

Fig. 4 is a similar view of a slightly modified construction.

Relating more in detail to the drawing, the sheet metal cap comprises a sleeve-like body 1 closed at its outer end by walls 2 35 and having its inner end inturned and contracted about the bolt 3 to provide a shoulder 4 between which and a shoulder 5 is confined a coiled spring 6 for urging the cap onto the bolt. The latter is formed 40 with a longitudinal bore 7 from which leads a lateral oil duct 8 which is normally closed by the closure cap.

A solid tapering plug 9 is arranged within the cap with its flat outer side contacting the comparatively frail end wall 2 to reinforce the same so that when the plug is driven into the bore 7 of the bolt, said plug will present a solid head for receiving the hammer blow and consequently relieve the 50 end wall 2 from the force of the blows and thereby eliminate crushing or disfiguring the same. The plug 9 is formed with a peripheral flange that extends beyond the periphery of the bolt to form the shoulder 5.

In Fig. 4 there is illustrated a further

embodiment of the invention in which the peripheral flange or head 10 of the tapered plug 9 is driven against a ring or washer 11 so that the latter constitutes one of the confining shoulders for the coiled spring. 60

In either form, the device is preferably assembled as a unit, such as is indicated in Fig. 3, and marketed in this manner it being noted that the spring serves to retain the plug in the cap. In mounting the device, the small end of the plug is inserted in the bore of the bolt or the like, and forceful blows applied to the end wall 2 to drive the plug firmly to position. The lateral oil duct will then be covered by the cap body, 70 in which connection it will be noted that there are no other oil holes, and that the plug is solid thus greatly reinforcing the bolt.

The meritorious structure thus provided is simple in construction and easily assembled, and since the force of the hammer is taken up by the solid plug the cap will not collapse as would be the case should the plug be made from sheet metal and in hollow form. The plug will never become lost when off the bolt for the coiled spring firmly holds the same against the end walls. 80

What is claimed is—

1. A lubricator for hollow bolts, comprising a cap body closed at one end and opened at its opposite end, the opened end being inturned to form a shoulder, a solid tapered plug arranged within the cap body and having a head seating against the closed end thereof, and a coiled spring confined between the head of the plug and the shoulder of the cap body. 85

2. A lubricator for hollow bolts having a lateral oil duct, comprising a sleeve-like body for covering the oil duct, said body closed at one end by an end wall and having its opposite end opened, means for reinforcing the end wall and securing the body to the bolt, and means for yieldably urging the body onto the bolt. 95

3. A lubricator for hollow bolts, comprising a cap body closed at one end and having its opposite end opened, a reinforcing and securing plug arranged within the cap, and means for holding the plug in position. 105

4. A lubricator for hollow bolts, comprising a cap body closed at one end and having its opposite end opened, a cap-reinforcing plug disposed therein loosely against 110

the closed end of the cap and having its inner end prepared for being driven into the hollow bolt, and means for yieldably securing the plug in position.

5. 5. A lubricator for hollow bolts, comprising a cap body closed at one end and having its opposite end opened, said opened end portion being provided with a shoulder, a headed tapered plug freely disposed in the body for reinforcing the closed end thereof and for being driven into a hollow bolt, a washer engaged with a head and forming a shoulder opposing the first shoulder, and a spring confined between the shoulders.
- 10 in the body for reinforcing the closed end thereof and for being driven into a hollow bolt, and a resilient element interposed between the head and the shoulder.

6. A lubricator for hollow bolts, comprising a cap body closed at one end and hav-

ing its opposite end opened, said opened end portion being provided with a shoulder, a headed tapered plug freely disposed in the body for reinforcing the closed end thereof and for being driven into a hollow bolt, a washer engaged with a head and forming a shoulder opposing the first shoulder, and a spring confined between the shoulders.

20 In testimony whereof I affix my signature in presence of two witnesses.

NORMAN W. CUMMINS.
